US0D1045002S

(12) **United States Design Patent** (10) **Patent No.:** **US D1,045,002 S**
Aral (45) **Date of Patent:** **** Oct. 1, 2024**

(54) **GUN SIGHT**

(71) Applicant: **SAMSUN YURT SAVUNMA SANAYI VE TICARET ANONIM SIRKETI, Samsun (TR)**

(72) Inventor: **Cahit Utku Aral, Istanbul (TR)**

(73) Assignee: **Samsun Yurt Savunma Sanayi Ve Ticaret Anonim Sirketi Corporation, Tekkeköy Samsun (TR)**

(**) Term: **15 Years**

(21) Appl. No.: **35/515,413**

(22) Filed: **Jul. 18, 2022**

(80) **Hague Agreement Data**

Int. Filing Date: **Jul. 18, 2022**

Int. Reg. No.: **DM/224051**

Int. Reg. Date: **Jul. 18, 2022**

Int. Reg. Pub. Date: **Oct. 21, 2022**

(51) **LOC (14) Cl. 22-01**

(52) **U.S. Cl.**

USPC **D22/109**

(58) **Field of Classification Search**

USPC D22/108, 109, 110, 199; D16/130
